UNITED STATES PATENT OFFICE.

JOSEPH H. PARKER, JR., OF WOBURN, MASSACHUSETTS.

DESIGN FOR A CHAIR.

SPECIFICATION forming part of Design No. 29,804, dated September 6, 1898.

Application filed May 18, 1898. Serial No. 681,082. Term of patent 3½ years.

To all whom it may concern:

Be it known that I, JOSEPH H. PARKER, Jr., of Woburn, in the county of Middlesex and State of Massachusetts, have invented and produced a certain new and original Design 5 for a Chair, of which the following is a specification, reference being had to the accompanying drawing, forming a part thereof.

This invention relates to a new and original 10 design for a chair or other similar articles of furniture; and it consists in the novel features of shape and configuration and contrast hereinafter fully described and claimed, and clearly illustrated in the accompanying drawing, which is a perspective view showing in 15 entirety a chair embodying my design.

In its entirety the article of manufacture embodying my design is shown as a rocking-chair having a substantially rectangular seat 20 2, supported upon standards 3 3 and 4 4, which are in turn mounted at their lower ends on rockers. The standards 3 3 project upwardly beyond the seat, and arms 5 5 connect them with the rear standards or uprights 4 4, the 25 upper ends of which are indicated at *a a*.

The leading or characteristic features of my 30 design, therefore, comprise the shape or configuration of the chair, as above noted, and the peculiar conformation and delineation of the back of the chair, together with the arrangement of the various parts thereof to present contrasting colors or shades, thereby affording a pleasing appearance to the eye.

Said back of the chair is provided with two uprights *a a*, between which the portion *b* extends, the latter being shown as rectangular. 35 The said portion *b* is woven of cane in contrasting alternating stripes *c c'*. The first six stripes extend entirely thereacross, and the succeeding seven stripes of contrasting color 40 extend partially across the same. The space at the upper left corner *e* not covered by the stripes is of a third contrasting color. A geometrical design, consisting of strips of cane 45 *d* of a color contrasting to that of the space *e*, is formed in the square space *e*, the strips of cane being crossed to form the appearance of stars. The back of the chair presents the appearance of a flag or emblem supported at both sides by standards. The face of the portion *b* is undulatory or waving, as indicated, 50 and at the top and bottom edges of the same there are cross-bars, whereby the whole geometrical design, with its contrasting shades and colors, is confined within a frame comprising 55 the said cross-bars and the uprights *a a*.

I claim—

The design for a chair, substantially as shown and described.

In testimony whereof I have affixed my signature in presence of two witnesses.

JOSEPH H. PARKER, JR.
